US00D896883S

(12) **United States Design Patent** (10) Patent No.: **US D896,883 S**
Ohashi et al. (45) Date of Patent: **** Sep. 22, 2020**

(54) **INK CARTRIDGE FOR COMPUTER
PRINTERS**

(71) Applicant: **CANON KABUSHIKI KAISHA**,
Tokyo (JP)

(72) Inventors: **Tetsuya Ohashi**, Tokyo (JP); **Ryoji Inoue**, Tokyo (JP); **Hironori Murakami**, Tokyo (JP); **Takeho Miyashita**, Tokyo (JP); **Takashi Fukushima**, Tokyo (JP); **Yasuo Kotaki**, Tokyo (JP); **Kyosuke Nagaoka**, Tokyo (JP)

(**) Term: **15 Years**

(21) Appl. No.: **35/506,485**

(22) Filed: **Sep. 28, 2018**

(80) **Hague Agreement Data**

Int. Filing Date: **Sep. 28, 2018**

Int. Reg. No.: **DM/200220**

Int. Reg. Date: **Sep. 28, 2018**

Int. Reg. Pub. Date: **Mar. 29, 2019**

(30) **Foreign Application Priority Data**

Mar. 29, 2018 (JP) 2018-006724
Mar. 29, 2018 (JP) 2018-006725

(51) **LOC (12) Cl.** **16-03**

(52) **U.S. Cl.** **D18/43**
USPC **D18/43**

(58) **Field of Classification Search**

Primary Examiner — Robert M. Spear

(57) **CLAIM**

The ornamental design for an ink cartridge for computer printers, as shown and described.

DESCRIPTION

- 1.1—Right side elevational view;
- 1.2—Left side elevational view;
- 1.3—Top plan view;
- 1.4—Bottom plan view;
- 1.5—Front elevational view;
- 1.6—Rear elevational view;
- 1.7—Top front perspective view;
- 1.8—Bottom front perspective view;
- 1.9—Top rear perspective view;
- 1.10—Bottom rear perspective view;
- 2.1—Right side elevational view;
- 2.2—Left side elevational view;
- 2.3—Top plan view;
- 2.4—Bottom plan view;
- 2.5—Front elevational view;
- 2.6—Rear elevational view;
- 2.7—Top front perspective view;
- 2.8—Bottom front perspective view;
- 2.9—Top rear perspective view;

(Continued)

2.10—Bottom rear perspective view.

1 Claim, 20 Drawing Sheets
